G. MATSUSHITA

COMBINED COLLAPSIBLE CHAIR AND BED

Filed April 1, 1924

INVENTOR:
GENTARO MATSUSHITA.

Br ATTY: *Eduardo M. Kojima*

UNITED STATES PATENT OFFICE.

GENTARO MATSUSHITA, OF SELMA, CALIFORNIA.

COMBINED COLLAPSIBLE CHAIR AND BED.

Application filed April 1, 1924. Serial No. 703,432.

To all whom it may concern:

Be it known that I, GENTARO MATSUSHITA, a subject of the Emperor of Japan, residing at Selma, in the county of Fresno and State of California, have invented a new and useful Combined Collapsible Chair and Bed, of which the following is a specification.

This invention relates to improvements in a combined chair and bed, and specifically to one which may be set up as a chair or a bed, and which may be folded in a more compact form for packing and shipping, and to one provided with means for securely holding in desired relation the several parts in any of its collapsed or set up positions.

Another object is to so proportion and form the several cooperating parts of the device that when it is in collapsed form, they shall lie closely contiguous and compact to eliminate as far as practicable, any liability of injury when being shipped in collapsed form, and which shall be securely locked when in position for use as a chair or portable cot.

In the drawings, Figure 1 is a side elevation of the device as set up for use as a cot. Fig. 2 is a perspective view of the device as set up for use as a chair. Fig. 3 is a side elevation of the device in collapsed position for shipment. Fig. 4 is a vertical mid-section of the device when set up as a chair.

Referring to the drawings, I construct a central frame section 11, formed by the side bars 12, brackets 13, and a metal cross-bar 14. The bar 14, forms the top of the device, when set up as a chair. A head frame section 15, is formed by the side bars 16, and by a cross-bar 17, and is connected to the central section by hinges 18. The foot-frame section 10, is formed by the side bars 19, and a cross-bar 20, and is connected to the central section by hinges 21. Supporting elements 22, connected by a cross-bar 23, are connected by hinges 24, with the foot section 10, and, when the device is set up as a chair, form the front legs thereof, and when the device is set up as a cot, serve to support the foot thereof.

When in the set up position, the supporting elements 25, connected by a brace 26, and connected to central frame section 15, by a pivot bar 27, serve as the rear legs of the chair, and as a support for the head of the cot. A canvas fabric 28, is connected

at one end to pivot bar 27, and at the opposite end to cross-bar 20. When the device is set up as a chair, the fabric element passes over cross-bar 14, at the top of the chair.

Arranged on each side bar 16, of the head frame section 15, are the projections 29, adapted to be engaged by hooks 30, carried by the central frame section 11, when the parts are folded. The central frame section 11, is provided with metal extensions 31, which, when the device is set up as a cot, abut against frame members 19, and in recesses 32. Metal loops 33, slidable upon frame members 19, are adapted to engage with extensions 31, to hold the frame sections rigidly in open set up position. The supporting members 22, are provided with metal extensions 34, having each a knuckle end 35, to which the brace member 36, is connected. When the device is set up as a chair, the brace member 36, extends through the upper portion of slots 37, in members 12. In this position the brace member 36 abuts against cross-bar 17, serving to retain the brace member 36 in engagement with the upper extremities of slots 37.

A brace member 38 is connected to cross-bar 26. When the device is set up as a cot, the bar 38 engages with metal cross-bar 14, and when the device is set up as a chair, this brace bar engages with a bracket 39, depending from cross-bar 20. This arrangement serves to prevent outward movement of the supporting elements 25. To prevent an inward movement of elements 25, I have provided hooks 40, adapted to engage with corresponding notches 41, in supporting members 25.

In collapsing the device for shipping, the brace member 36 is forced manually from engagement with the extremities of slots 37, and the central frame section and foot frame sections are folded upon one another. The central and head frame sections are folded upon one another, and retained in position by hooks 30 in engagement with projections 29. The supporting elements are then folded upon the frame elements as shown.

What is claimed is:

1. Collapsible main frame elements including a central and two end frame sections, hinges connecting the central frame section with the end frame sections, said central frame section having slots in opposite sides thereof, supporting elements hingedly connected to one end frame section,

and including metal extensions, knuckles forming the extremities of said extensions, a bail member hingedly connected to said knuckles and extending through said slots, 5 said bail member engaging with the upper extremities of said slots in the set up position of the device, and serving to hold the said supporting elements in a rigid position relative to the main frame elements, other 10 supporting elements hingedly connected to the main frame elements on the opposite end thereof, including notched ends, hooks carried by the central frame section and adapted to engage with said notches in the 15 set up position, and a brace element connecting the central frame section and the hingedly connected supporting elements to cooperate with said hooks.

2. A collapsible device including a central and two end frame sections, said central frame section having slots in the sides thereof and said slots each having a notch at its upper extremity, supporting elements for the head end frame section, means for locking said supporting elements in fixed 20 relation with the end frame section, other supporting elements for the foot end frame section, metal extensions on the last-named supporting elements, and a bail member 25 hingedly connected to said metal extensions, and engaging at its opposite end with said notches in the set up position of the device, and said bail member bearing against the central frame section in its set up position 30 to prevent displacement from said notches.

3. A collapsible device including a central and two end frame sections, means for holding the central and one end frame section together including projecting lugs on 40 the end frame section, hooks on the central frame section adapted to engage with said lugs to hold the frame sections together in

locked position, supporting elements for the central and end frame sections having rounded and notched ends, said supporting 45 elements being hingedly connected to said end frame section, hooks mounted on the end frame section and engaging with the notches in said rounded ends, supporting means for the remaining end frame section, 50 means for locking said supporting means in fixed relation to said end frame section, and in fixed relation to the central and opposite end frame section, a brace loosely connected to the first-named supporting elements, and a bracket depending from the last-named section, said brace engaging with said bracket. 55

4. A collapsible device including a plurality of hingedly connected frame members adapted to assume three positions, means for locking the frame members in the several positions, said frame sections including a central frame member, a head frame member and a foot frame member, a pair of depending brackets on the central frame member, a crossbar integral with said depending brackets, a depending bracket integral with the foot frame member, supporting elements hingedly connected to the head 60 frame member, a brace member loosely connected to said supporting elements and adapted to engage with the first-named crossbar in one set up position, and with the depending bracket in another set up position, other supporting elements hingedly 65 connected to the foot frame member, extensions integral with the last-named supporting elements, and a bail member hingedly connected to said extensions and engaging 70 with the central frame member. 75

In testimony whereof, I hereunto affix my signature.

GENTARO MATSUSHITA.
